(57) **CLAIM**

The ornamental design for a base for a table as shown and described.

DESCRIPTION

FIG. 1 is a top perspective view of a base for a table according to a first embodiment of the design;

FIG. 2 is a front elevation view thereof to which right, left, and rear elevation views are identical;

FIG. 3 is a top plan view thereof;

FIG. 4 is a bottom plan view thereof;

FIG. 5 is a bottom perspective view thereof;

FIG. 6 is a top perspective view of a base for a table according to a second embodiment of the design;

FIG. 7 is a front elevation view thereof to which a rear elevation view is identical;

FIG. 8 is a right side elevation view thereof;

FIG. 9 is a left side elevation view thereof;

FIG. 10 is a top plan view thereof;

FIG. 11 is a bottom plan view thereof;

FIG. 12 is a bottom perspective view thereof;

FIG. 13 is a top perspective view of a base for a table according to a third embodiment of the design;

FIG. 14 is a front elevation view thereof to which a rear elevation view is identical;

FIG. 15 is a right side elevation view thereof;

FIG. 16 is a left side elevation view thereof;

FIG. 17 is a top plan view thereof;

FIG. 18 is a bottom plan view thereof;

FIG. 19 is a bottom perspective view thereof;

FIG. 20 is a top perspective view of a base for a table according to a fourth embodiment of the design;

FIG. 21 is a front elevation view thereof to which a rear elevation view is identical;

FIG. 22 is a right side elevation view thereof;

FIG. 23 is a left side elevation view thereof;

FIG. 24 is a top plan view thereof;

FIG. 25 is a bottom plan view thereof; and,

FIG. 26 is a bottom perspective view thereof.

(Continued)

The portions of the article shown in broken line form no part of the claimed design with broken lines adjacent shaded portions of the article forming the bounds of the claimed design.
